US00D623524S

(12) **United States Design Patent**
Toh et al.

(10) **Patent No.:** **US D623,524 S**
(45) **Date of Patent:** ** *Sep. 14, 2010

(54) **CONTAINER**

(75) Inventors: **Kiat Cheong Toh**, Forest Hills, NY (US); **John Lamb**, Pewsey (GB); **Will Maskell**, Marlborough (GB); **Alan Whiting**, Penrith (GB); **Tom Walton**, Shipston-on-Stour (GB); **Corinne Elstow**, Marlborough (GB)

(73) Assignee: **Colgate-Palmolive Company**, New York, NY (US)

(**) Term: **14 Years**

(21) Appl. No.: **29/339,425**

(22) Filed: **Jun. 30, 2009**

(51) LOC (9) Cl. **09-01**

(52) U.S. Cl. **D9/516**

(58) Field of Classification Search D9/516, D9/522, 523, 526, 530, 541, 543, 549, 550, D9/551, 552, 563, 564, 565, 571, 575, 434; 215/381-385

(57) **CLAIM**

The ornamental design for a container, as shown and described.

DESCRIPTION

FIG. 1 is a front, right, perspective view of a container showing our new design;

FIG. 2 is a front, left, perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of a top portion of a container and a bottom portion of a container is included for the purpose of illustrating only and forms no part of the claimed design.

1 Claim, 7 Drawing Sheets
